UNITED STATES PATENT OFFICE.

CHARLES A. MEZGER, OF BROOKLYN, NEW YORK.

SPARK-PLUG AND METHOD OF MAKING THE SAME.

1,286,384.

Specification of Letters Patent.

Patented Dec. 3, 1918.

Continuation of application Serial No. 395,678, filed October 3, 1907. This application filed January 31, 1917.
Serial No. 145,582.

To all whom it may concern:

Be it known that I, CHARLES A. MEZGER, a citizen of the United States, and a resident of borough of Brooklyn, county of Kings, city and State of New York, have invented certain new and useful Improvements in Spark-Plugs and Methods of Making the Same, of which the following is a description in such full, clear, and exact terms as 10 will enable any person skilled in the art to which it pertains to make and use the same.

My invention relates to the manufacture of spark plugs for internal combustion or explosive engines.

15 Heretofore the practice in this art has generally been to form the body of the plug by boring and turning it from a solid bar of hexagonal or other shaped metal involving losses both in labor and material. My 20 invention seeks to save these losses and produce a better article at less expense than that heretofore involved.

I attain this end by forming the body portion of the plug from metal by stamping, 25 drawing, pressing or spinning the same up into the requisite form, whereby I not only save a great amount of metal but a corresponding saving in labor and time is effected.

My invention involves other features of 30 importance all of which will be fully set forth hereinafter and particularly pointed out in the claims.

The accompanying drawings show the improved method of making the spark plug 35 as well as various preferred forms of the same, and in these drawings—

Figures 1 to 5 show the successive operations of drawing up the body blank from a flat sheet of metal.

40 Figs. 6 to 12, 15 to 20, 26, and 29 to 35 are detailed views showing the various forms of spark plug bodies and other parts produced by and in accordance with my invention, the details of which will be fully set forth 45 hereinafter.

Figs. 13, 14, 21 to 25, 27, 28 and 36 illustrate the tools employed in accordance with my invention and the process thereof as will also be fully set forth hereinafter.

50 Referring to Figs. 1 to 5, 40 indicates the circular blank of sheet metal of which I form a cupped blank or a blank tube from either of which I form the spark plug body in preference to cutting tube blanks from 55 lengths of tubing. This blank is drawn up

into cupped form by any of the well-known methods of stamping, pressing, spinning or otherwise as indicated at 41 in Fig. 2. A number of different stages may have to be resorted to to prevent doing violence to the 60 metal as will be understood by metal workers. 42, Fig. 3, shows another stage of the progressive cupping of the metal and 43 Fig. 4, shows what may be supposed to represent the final cupping operation. It is unimportant to my invention how many stages are employed in this cupping operation. This will depend upon the character of the metal and the depth and form of the cup of which the spark plug body is made. 44, in Fig. 70 5, represents a further stage in the drawing operation which may be resorted to if desired according to which the lower part of the cup is rolled in or compressed as the drawing shows.

75 The closed end of the cup blank Fig. #4, may be cut or punched out, thus to form a tubular blank instead of the end being removed after subsequent operations as described hereinafter.

80 Figs. 6 and 7 illustrate the next step in the operation according to which the spark plug body is worked into shape, comprising a collar 45, at its upper end adapted to be internally threaded to receive a gland for 85 holding the porcelain or other insulation in place as will be hereinafter described; a hexagonal portion 46 for the application of a wrench; a double bend 47 to receive and hold a collar 48; a cylindrical portion 49 to 90 be externally threaded to screw into the engine cylinder; and finally, a reduced inner portion 50 which is subsequently punched or bored out on its lower part to allow the electrode to project centrally from the plug as 95 will be fully understood and is illustrated in figures of the drawings to be hereinafter described.

100 Referring to Fig. 8 it will be noted that the structure there shown resembles that shown in Fig. 6 excepting that the reduced part 50^a is tapered slightly and has a further construction 51 at its inner or lower end. The construction shown in Fig. 8 is further different from that shown in Figs. 6 and 7 105 in that no provision is made for the application of a ring or gasket such as the element 48 in Figs. 6 and 7. Fig. 8, 49^a represents the part to be externally threaded, 46^a represents the hexagonal portion, and 45^a 110

represents the collar which is to be internally threaded to receive the gland.

Figs. 9 and 10 show another form of the spark plug body which is drawn up as before described and formed with three diameters 52, 53 and 54, the latter being a tapered form as shown. In producing this shape the metal may be drawn up into a general conical form through the agency 10 of the stamping, spinning or drawing operation and if desired, may then be subjected to the action of a turning or cutting tool such as a lathe by which the various diameters and shapes shown in Figs. 9 and 10 are secured. In this construction it will be noted that different thicknesses of metal are indicated in the section Fig. 10 which different thicknesses of metal are best obtained by the turning operation whereas upon referring to Figs. 6 and 8, for example, it will be seen that the metal thicknesses are formed at all points which indicates that the operation there is strictly a drawing operation from a plate of metal of uniform 25 thickness.

After the blank body is formed as in Figs. 9 and 10 the part 52 must be transformed into a hexagonal shape 52^a as shown in Figs. 11 and 12 and a gasket ring 55 (dotted lines 30 Figs. 11 and 12) may be applied. The shaping of the hexagonal portion 52^a, Fig. 12, from the round portion 52, Fig. 10, is preferably effected in a die such as shown in Figs. 13 and 14 and combined with a suitable 35 plunger tool which is entered into the end 52 of the body shown in Fig. 10 and forces said body through the die. This die consists of a ring 56 with a hexagonal inner shape 57. The blank body shown in Fig. 10 is driven down through this die block, Fig. 6, Figs. 13 and 14, with the plunger tool inserted in the end 52 and the metal is thereby forced to change its form from the circular form 52 of Fig. 10 for the hexagonal form 52^a of Fig. 12.

Referring to Figs. 15 and 16 it will be noted that these illustrate a spark plug body which is reversed with respect to that shown in some of the other figures, for example, Figs. 6 and 8. In Figs. 6 and 8 the hexagonal portion is on the open end of the cup whereas in Figs. 15 and 16 the hexagonal portion 58 is formed on the closed end of the cup. This cup in Figs. 15 and 16 is produced by a pure drawing or compressing operation without any turning or machine tool work excepting that the closed upper end of the plug indicated at 59 in Figs. 15 and 16 must be punched out or pierced and 60 a flange similar to that designated 45 in Fig. 6, for example, turned up from the metal in the end 59 so as to form an 65 standing collar which may subsequently be internally threaded to receive the gland or ring which holds in place the porcelain or

other insulation. Still referring to Figs. 15 and 16, after the closed end 59 of the body has been treated as described the lower part of the body may then be pressed, drawn, rolled or otherwise reduced in diameter as 70 indicated by the broken lines 60 in Fig. 16 thus giving the necessary shape to the inner part of the plug body or shell as will be understood from the previously described figures. 75

Fig. 17 illustrates a form of the drawn, stamped or spun spark plug body in which the same is made in two drawn or stamped parts 61 and 62 united by a welt or other seam 63. Sometime it may be advantageous 80 to form the spark plug body in two drawn sections rather than in one as previously described herein and Fig. 17 is to illustrate this two-part formation. It will be noted that the essential elements of the spark plug 85 body as heretofore described are preserved in the structure shown in Fig. 17 i. e. 61^a is the upstanding collar to be internally threaded to receive the gland, 61^b is the hexagonal portion for the wrench, 62^a, the 90 cylindrical portion to be externally threaded to screw into the cylinder of the engine and 62^b a tapering open end which permits the expansion of the central electrode from the body and finishes off the plug. 95

I have heretofore referred to the gland which is screwed into the open outer end of the spark plug body to hold the porcelain or other insulation in place. One form of this gland is shown in Figs. 18, 19 and 20. 100 Referring to these figures 64 indicates the cylindrical portion of the gland which is intended to be externally threaded to screw into the open outer end of the spark plug body and 65 indicates a hexagonal portion 105 to facilitate the application of a wrench. 66 indicates a packing ring or gasket which is placed under the enlarged hexagonal portion 65. Preferably the gland illustrated in Figs. 18 and 19 is formed of stamped or 110 drawn sheet metal in the same manner described in connection with the spark plug bodies heretofore described in Figs. 6 and 8 and 15 and 16 for example. This gland would be formed by stamping so that a cup 115 is first produced and then the closed end of the cup is compressed in a suitable die so that the enlarged hexagonal portion 65 is produced. The closed end of the cup in Fig. 19 is then punched open as indicated by 120 the broken lines 67 in said view producing the opening through the gland through which the insulation projects.

Going back to Figs. 5 and 6 before described, and referring to Figs. 21 to 23 in 125 connection therewith, Figs. 21 to 23 illustrate a metal drawing or pressing tool adapted to take a blank tube or the blank cup such as shown in Fig. 4 and transform the same into the body shape shown in Fig. 6. 130

These Figs. 21 to 23 also illustrate particularly the manner in which the hexagonal portion 46 is formed on the body of the spark plug. In these figures 68 indicates a frame or table in which a die block 69 is placed, the same having a cavity of 3 diameters indicated at 70, 71, and 72 in Figs. 21 and 23. On the table 68 is a water pan 73 which has an opening in its bottom so that the water therein may enter and fill the cavities of the die 69. Comparing with the die block 69 is a die block 74 of which Fig. 22 is an inverted plan or end view. This die block has a hexagonal cavity 75 in its open lower end above which is a reduced circular cavity 76. 78 are water relief passages placed at various points to permit the expansion of the water as will appear hereinafter. An ejector 79 operates in the bottom of the die 69 and a press plunger 80 operates over the die. This plunger has a stem 81 on the lower end of which the die section 74 is loosely carried. 82 is a spring which presses the section 74 down on the lower end of the stem 81. Within the stem 81, is a relief plug 83 pressed down by a spring 84 seated in a cavity in the plunger 81.

The operation of the device shown in Figs. 21 to 23 is as follows: The cup metal blank body such for example, has a cup 43 shown in Fig. 4, is placed in the lower die 69 in the position shown in Fig. 21 on top of the ejector 79. The pan 73 and the die 69 will have been previously filled with water or any other non-compressible liquid. This water fills the die 69 and fills the interior of the blank 43 and lies in the pan 73 over the top of the blank as shown. The blank is then inserted into the lower die section 69 when the press plunger 80 is raised and the die section 74 stands up above the surface of the water and indeed above the top edge of the pan 73. The press plunger 80 now descends and when the parts reach the position shown in Fig. 21 it will be noted that the lower part of the die section 74 is submerged in the water, the water completely fills the blank 43 and also fills the interior of the die section 43. The relief plunger 83 enters the open upper end of the body section. The press plunger does not pause, however, at this point but continues its downward movement, the spring 82 yielding to allow the plunger stem 81 to move down in the die section 74 which die section can at this time move no farther owing to the fact that it has "fetched up" on top of the die 69. The result of this continued downward movement of the plunger stem is important. The water within the blank 43 is trapped therein and cannot escape (the open upper end of the blank having been previously joined with the lower end of the plunger stem 81), the water in

the die section 74 outside of the blank and in the die section 69 outside of the blank 43 is free, however, to be discharged through the various relief openings 78. In the continued downward movement of the plunger 70 stem 81 pressing on the spark plug body 43 and the water trapped within the body making it impossible for the body to collapse under the crushing strain of the plunger, said body will be forced to expand within and 75 conform to the shapes of the cavities in the die sections 69 and 74 and the body will take the form of the interior walls of said cavities. Comparing Fig. 6 with Fig. 21 it will be noted that the part 50 of the blank in 80 Fig. 6 is shaped by the upper part of the cavity 72, the part 49 is shaped by the enlarged cavity 71, the hexagonal portion 46 is shaped and formed by the cavity 75 of the die section 74 which cavity is hexagonal in 85 form as indicated by the broken lines in Fig. 21, and the upstanding collar 45 is formed by the lower part of the cavity 76 in the die section 74. 48 in Fig. 21 indicates the packing ring shown in Fig. 6 which 90 packing ring 48 is placed loosely in the cavity 70 of the die section 69 before the die section 74 descends to the position shown in Fig. 21. Then the crushing strain which the plunger arm exerts on top of the body 95 blank 43 combined with the forms of the cavities in the die blocks as before described and with the action of the water within said blank which makes it impossible for the blank to collapse, causes the metal plate of 100 which the blank is formed to bend itself around the gasket 48. The metal of the blank thus bends around the inner edge of the gasket because the resistance to this bending is less than the resistance to the disruption of the ring 48. This is true since the ring 48 is firmly held and pressed in the cavity 70 of the die section 69 and the strain is edge-wise on the ring whereas the bending strain on the body section is sidewise to 105 the metal thickness and the body section is therefore forced to give and fold itself around the ring. The relief plunger 83 is provided simply to account for any change in the interior volume of the blank 43 and 110 its changes from the shape shown in Fig. 6 to that shown in Fig. 16. The water in the blank cannot escape and it is a purpose of my process to prevent its escape so that the relief plunger is provided to give way 115 slightly and only to that extent required by any change in the interior capacity of the plug body due to changing its form as described. When the operation above described is performed the press plunger 80 is 120 raised and lifts with it the die section 74. The ejector 79 then is operated to throw out the pressed spark plug body which assumes the shape and character illustrated in Fig. 6, the gasket ring 48, of course, com- 125 130

ing out with the body being indeed an inseparable part thereof owing to the operations before described.

Figs. 24 to 28 will, it is thought, be easily understood from the foregoing description of Figs. 21 to 23. Fig. 26 illustrates the finished spark plug body resulting from the operation of the die shown in Figs. 24, 25 and 27 and 28, excepting, of course, that the threads on the spark plug body must be performed in the usual threading machine. In Fig. 26 85 indicates an upstanding flange which is internally threaded to receive the gland such for instance as that shown in Fig. 19, 86 indicates the hexagonal portion 87, a cylindrical portion below the hex and 88 the threaded inner part of the body which screws into the cylinder head.

Still referring to Figs. 24, 25, 27 and 28, a cupped or tube blank such as blank 44 in Fig. 5 is inserted into the die 89. In the figures now being described there is but one die section which has a cavity of various diameters terminating in the hexagonal portion 90 at the top of the die. 91 is the water pan similar to that before described in connection with Fig. 21. 92 is the press plunger which has a stem 93, the lower end of which is raised as indicated at 94 to embrace the upper end of the blank 43. This raised end of the plunger stem confines the upper end of the blank and as the plunger stem continues to descend from the position shown in Fig. 25 to the position shown in Fig. 26 the upper extremity of the blank 44 is confined by the raised plunger stem and the lower cavities of the die 89 confine and hold the shape of the lower part of the body 44. The crushing of the body consequently leaves but one movement of the metal possible and that is expansion of the upper portion of the blank outward into the hexagonal cavity 90 of the die 89 and gives the blank the form shown in Fig. 25 which represents the extra downward movement of the press plunger stem 93. The stem is then withdrawn and the body is thrown out by the ejector 95. Fig. 27 is a plan view of the die 89 and shows the hexagonal cavity 90 in the upper part thereof which conforms exactly to the cross-sectional shape of the stem 93 as indicated at 94 and Fig. 28 is a bottom end view of the stem 93 showing the cavity 94 which receives the upper end of the body blank as before described. When the body blank is thrown out of the die after having been shaped as shown in Fig. 25 the closed end thereof is opened by cutting it away with a suitable tool as indicated at 96 in Fig. 26 and the collar 85 is internally threaded and the part 88 externally threaded thus finishing the body blank.

Instead of forming the upstanding flange 45 or 45^a (Figs. 6 and 7) by the action

of the die devices shown in Figs. 21 and 24 I may form this upstanding flange by rolling the same against the mandrel as indicated in Fig. 36 where 97 indicates the roll and 98 the mandrel, the latter entering the open end of the body blank which is indicated at 99 in Fig. 36. The roll 97 swages or rolls in the body and forms the reduced upstanding collar. The particular device shown in Fig. 36 contemplates subsequently cutting off the surplus end 100 after the rolling operation shown in this figure has been performed.

In view of the foregoing description it is thought that the assembled spark plug views in Figs. 29, 30 and 31 will be easily understood.

Fig. 29 shows the plug assembled from the body blank illustrated in Figs. 9 to 12. The part 53 of the blank has been threaded externally and the part 52^a threaded internally. The tapered part 53 has been opened at its end to let the central electrode 101 protrude. 102 represents the usual porcelain with the enlargement 103 engaging gaskets 104 which are kept in place by the gland 64—65 formed preferably as shown in Figs. 18 and 19 with or without the gasket 66 of Fig. 20.

Fig. 30 shows the adaptation of the body of Fig. 8 to the assembled spark plug and it is believed that the body porcelain and conductors or electrodes will be obvious from the drawing. The gland 105 in Fig. 30 is preferably formed as in Fig. 19 before described with the gasket 66 of Figs. 18 to 20. The inner end of the gasket 105 is rolled in around the enlargement of the porcelain to confine a packing gasket 106 and the upper end carries a tapering gasket 107 preferably of metal which is fastened in the gland as shown. The gland therefore with the parts 106 and 107 and with or without the part 66 is permanently united to the porcelain of the spark plug and may be removed only with the porcelain.

Fig. 31 shows the spark plug body also of the general form illustrated in Fig. 6 but here the porcelain is permanently united with the body of the spark plug and there is no gland such as the element 64 of Figs. 19 and 29 or 105 of Fig. 30. This permanent union is effected by shouldering the porcelain against the gasket 108 on the lower side of the porcelain enlargement and a tapering metal ring gasket 109 on the upper side. After these parts are inserted the upstanding flange or neck 45 of the body formed as in Fig. 6 is rolled or crimped inward around the gasket 109 thus permanently fastening the porcelain in the body so that it cannot be removed, as well as clenching or clamping the packing 108 and 109 against the porcelain and disposing altogether of the

use of a gland such as is employed in Figs. 29 and 30. Figs. 32, 33, 34 and 35 are plan and sectional views of the gaskets 109 and 108, the form being a soft metal ring tapered in section and the latter an annular sheet metal casing inclosing an asbestos thread and adapted to be compressed between the porcelain body and shoulder as illustrated in Fig. 31.

10 As a result of said drawing operation, the grain of the metal in the finished article follows the form or shape of the latter. That is to say, the particles of the metal extend in directions parallel to the true contour of the body, as distinguished from a product that is cut to the desired shape, and where in the grain of the metal is all in one direction, regardless of exterior formation. This 15 enables the production of a considerably stronger body with a minimum mass and 20 weight of material, and at a consequent low cost.

This application is a continuation of my co-pending application filed October 3rd, 25 1907, Serial No. 395,678.

By the term "drawn" or "drawing," as used in the claims, I intend to cover all methods of shaping by bending, pressing, or die-shaping, through the various mechanical 30 agencies known for the purpose such as

metal stamps, presses, spinning rolls, and the like.

The term "metal blanks" as used in the claims is intended in its broad interpretation to cover flat metal blanks, metal cups, metal tubes, or any form of metal blank requiring 35 additional drawing, pressing, spinning, or rolling operation to shape it into the form of a spark plug body.

What I claim is:—

1. The method of making a spark plug body having a cylindrical portion adapted to be exteriorly threaded and an angular tool engaging portion, which consists in first drawing a metal blank into hollow form and subsequently submitting it to a die-shaping operation for making the angular tool engaging portion. 40

2. A spark plug body consisting of a drawn metal sleeve having a cylindrical portion adapted to be exteriorly threaded and 45 an angular tool engaging portion. 50

In testimony whereof I have hereunto signed my name in the presence of two witnesses.

CHARLES A. MEZGER.

Witnesses:
